UNITED STATES PATENT OFFICE.

WILLIAM D. GRAY, OF MILWAUKEE, WISCONSIN, ASSIGNOR, BY MESNE ASSIGNMENTS, TO ALLIS-CHALMERS COMPANY, A CORPORATION OF NEW JERSEY.

SHAKING-SIEVE AND CLEANER THEREFOR.

SPECIFICATION forming part of Letters Patent No. 752,448, dated February 16, 1904.

Application filed November 19, 1900. Serial No. 37,005. (No model.)

To all whom it may concern:

Be it known that I, WILLIAM D. GRAY, a citizen of the United States, residing at Milwaukee, in the county of Milwaukee and State 5 of Wisconsin, have invented certain new and useful Improvements in Shaking-Sieves and Cleaners Therefor, of which the following is a specification.

My present invention pertains to improvements in shaking-sieves and cleaners therefor, the construction and advantages of which will be hereinafter set forth.

This invention, which is in the nature of an improvement upon or modification of my previous patent, numbered 660,569, dated October 30, 1900, will be found fully shown in the annexed drawings, wherein—

Figure 1 is a perspective view of a sieve-section, a portion of the bolting-cloth being omitted and a portion of the lining being shown away from the frame; Fig. 2, a longitudinal sectional view of Fig. 1; Fig. 3, a perspective view of the brush; Fig. 4, a similar view looking at the opposite side, and Fig. 5 a sectional view illustrating a modification of the brush structure and the manner of constructing the same.

The object of the present invention is to provide an improved form of cleaning-brush for the sieve and also to provide a new or modified form of lining for the interior face of the sieve-frame.

Referring to the drawings, A designates the frame of a sieve or sieve-section, having secured to its lower face a wire net or similar foraminous surface B, while the upper side or face is provided with the usual sieve-cloth C. The interior face of the sieve-frame is lined with a strip of material D—such, for instance, as leather—to resist the action of the cleaning-brush, which would otherwise wear or cut away the frame, usually constructed of soft wood. Within the sieve-section thus formed is placed one or more cleaning-brushes. The brush, as illustrated in Figs. 3 and 4, comprises a metal back E cup shape in form and provided with a rounded projection or protuber-

ance F centrally formed thereon. Within the cup-shaped metallic back is seated the brush-body G, formed of wood, leather, or the like, 50 carrying a series of bristle-tufts H. After said body is in place the edge of the back is turned inwardly over said body, as indicated at a, Fig. 5, firmly securing the body and back together, and this without the use of any separate fastening device. The rounded projection F is of such size relative to the openings in the wire-netting that it may pass partly into said openings. Consequently when the brush is moved or thrown about in the sieve-frame 60 the projection rides over the wires, causing the brush to tip or tilt, and this tipping or tilting motion serves to project the bristles through the meshes of the cloth and thoroughly clean the same.

In Fig. 5 a modified construction of brush is shown, wherein instead of forming the round projection or protuberance centrally of the brush-back it is placed eccentric thereto. Under this formation the bristles farthest 70 from the protuberance are given a wider range of movement or, in other words, have imparted to them a greater tipping or tilting motion than can be had with the projection or protuberance centrally located. The difference in action and range of the two forms is best illustrated by the full and dotted line positions of the two brushes. (Shown in Fig. 2.)

It is manifest that the protuberance eccentrically located may be employed in conjunction with brushes of other construction, though the form shown is preferred.

In use the brush, whether it be of the form shown in Fig. 4 or Fig. 5, is thrown about 85 within the frame beneath the sieve-surface by the action of the machine. In its travel over the wire-netting or other foraminous surface it tips or tilts, the bristles cleaning the surface of the bolting-cloth at times being projected through its meshes. The contact of the brush with the side of the frame of the sieve would, were it not for the leather or other yielding material secured thereon, in

time cut away the frame. The employment of the leather or other protecting strip, however, prevents such action.

Having thus described my invention, what 5 I claim is—

1. A brush for cleaning the sieves of sifting-machines and the like, comprising a main body portion carrying bristles, and a cup-shaped back having a rounded projection formed 10 thereon to one side of its center, the edge of the back being turned over on the face of the body portion after said body portion is seated within said back.

2. A brush for cleaning the sieves of sifting-15 machines and the like, comprising a main body portion carrying bristles, and a rounded projection on the back of the brush, said projec-

tion being located to one side of the axial center thereof.

3. A brush for cleaning the sieves of sifting- 20 machines and the like, comprising a main body portion of circular contour, a series of distinct and separated tufts of bristles extending up therefrom, and a rounded projection extending from the back of the brush, said projection being located to one side of the center. 25

In testimony whereof I have signed my name to this specification in the presence of two subscribing witnesses.

WILLIAM D. GRAY.
